US0D1101855S

(12) **United States Design Patent** (10) Patent No.: **US D1,101,855 S**
(45) Date of Patent: ** Nov. 11, 2025

(54) **CURVED BUTTON PANEL DISPLAY FOR AN ELECTRONIC GAMING MACHINE**

(71) Applicant: **Aristocrat Technologies Australia Pty Limited**, North Ryde (AU)

(72) Inventors: **Rajendrasinh B. Jadeja**, Las Vegas, NV (US); **Bruce Urban**, Las Vegas, NV (US)

(73) Assignee: **Aristocrat Technologies Australia Pty Limited**, North Ryde (AU)

(**) Term: **15 Years**

(21) Appl. No.: **29/968,893**

(22) Filed: **Oct. 18, 2024**
